UNITED STATES PATENT OFFICE.

PAUL KAMINSKI, OF BERLIN-PANKOW, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

SYSTEM FOR ADJUSTING AT A DISTANCE GUNS, SEARCHLIGHTS, OR OTHER APPARATUS.

Application filed May 12, 1921. Serial No. 468,968.

(GRANTED UNDER THE PROVISIONS OF THE ACT OF MARCH 3, 1921, 41 STAT. L., 1813.)

To all whom it may concern:

Be it known that I, PAUL KAMINSKI, a citizen of the German Empire, residing at Berlin-Pankow, Germany, have invented 5 certain new and useful Improvements in Systems for Adjusting at a Distance Guns, Searchlights, or Other Apparatus, of which the following is a specification.

In systems for adjusting at a distance 10 guns, search lights or other apparatus it has already been proposed to effect the supply of motor current for the different kinds of adjustment, as coarse and fine adjustments of the objects to be adjusted, by a 15 differential relay which is influenced by corresponding receivers.

Since, however, this influence is exerted by all receivers simultaneously it would be impossible to start the motor for correcting 20 the adjustment first effected in view of the simultaneous excitation of both windings by the opposing effect of the receivers. It is, therefore, necessary to insert resistances into the relay circuit.

According to the invention this disadvantage is avoided by providing a device at the receiver for one kind of adjustment, e. g. for coarse adjustment, this device starting the motor for that kind of adjustment, and by 25 simultaneously, during the period of its influence, hindering the receiver of the second kind of adjustment from being effective, e. g. by a switch disconnecting the circuit, controlled by the receiver of the second kind 30 of adjustment. Said switching device may be arranged only at the receiver for the one kind of adjustment, preferably for coarse adjustment, whereby in the working position of said device current is being supplied to the motor e. g. for coarse adjustment, whereas in the normal position of said device the current is supplied to the motor for fine adjustment. In this case the adjustment is effected directly over the corresponding receiver. However, a separate 35 switching device may be connected with each receiver. In this case the switching device of the receiver for coarse adjustment influences the switching device for the fine 40 adjustment.

In the drawings accompanying this speci-

fication and forming part thereof, my invention is shown in a purely diagrammatic form in which—

Fig. 1 shows an example of my invention in which two motors are used to adjust the object to be controlled; 55

Fig. 2 shows a similar form in which only one motor is controlled by both kinds of adjustment; 60

Fig. 3 shows an eddy current brake; and

Fig. 4 shows the arrangement of Fig. 2 with another system of connection for the eddy current brake.

In the system according to Fig. 1, the transmitting device G consists of two transmitters g_1, g_2 which are connected with each other in such a way that the one performs several revolutions, whereas the other for covering the entire range only makes one revolution. The two transmitters g_1, g_2 of which g_1 is designed for coarse adjustment and g_2 for fine adjustment cause a synchronous adjustment of the receivers e_1, e_2 , which in turn effect starting of the motors m_1, m_2 , respectively. On the shafts of the armatures of the receivers e_1, e_2 a contact s_1, s_2 is provided which is connected with the wire a of a current supply circuit and which contact, when adjusting the receiver armatures, will in each case be brought into connection respectively with other contacts l_1, r_1 or l_2, r_2 arranged upon discs k_1, k_2 , respectively, whereby the motor circuits will become closed according to the direction of revolution of the receiver armatures. The motor m_1 for coarse adjustment is operated by exciting one of its relays R_1 or R_2 in the circuits $+, a, s_1, l_1, R_1, b_1, -,$ or $+, a, s_1, r_1, R_2, b_1, -,$ respectively, where 70

by the relay armatures 1 or 2 are attracted and the contacts 3, 4, 5, 6 or 7, 8, 9, 10, respectively, are closed. As the field of the motor m_1 is constantly energized from the net as shown in the figure, the motor will start as soon as the circuit of its armature is closed. If the relay R_1 has been energized in the aforementioned manner and has attracted its armature, the circuit of the armature of m_1 is closed by way of $+$ pole, a , contacts 3, 4, left brush of the armature m_1 , right brush of the armature, contacts 75

95

100

5, 6, *b*, — pole. Whereas if the relay R_2 attracts its armature the circuit of the motor m_1 is as follows: + pole, *a*, contacts 7, 8, right brush of the motor's armature, left brush, contacts 9, 10, *b*, — pole.

As the direction of the current in the armature of motor m_1 is reversed by the two relays, the motor will also change the direction of revolutions. The motion of the motor m_1 is transmitted to the object to be adjusted by a differential gear P . Together with the object to be adjusted discs k_1, k_2 are rotated by a suitable gearing T until the contacts s_1, l_1 or s_1, r_1 , respectively, are opened and the motor is stopped accordingly. Though the receiver e_2 for fine adjustment is simultaneously actuated with the receiver e_1 , thus closing the contacts s_2, l_2 or s_2, r_2 the motor m_2 for fine adjustment is not operated since its starting circuit is broken at the other armature contacts 11 or 12 of the relays R_1 or R_2 . The coarse adjustment having been effected and relay R_1 or R_2 been deenergized accordingly, contact 11 or 12 referred to is closed when the motor m_2 is started and the fine adjustment of the object is effected by means of the differential gear P . The motor m_2 has a system of connections different from that of motor m_1 . The armature of motor m_2 is constantly energized from the net as follows: + pole, *a* resistance w_1 , armature m_2 , *b*, — pole. The left and the right winding of the field of the motor m_2 for the fine adjustment correspond in some way to the relays R_1, R_2 of the coarse adjustment. Only one of the windings of the field is energized when the motor m_2 is operating. When the motor m_1 has stopped and the contact s_2, r_2 of the receiver e_2 is closed the circuit of the field of the motor m_2 is as follows: + pole, *a*, s_2, r_2 , right-hand winding of the field, relay B , contacts 11 and 12 of the released relays R_1 and R_2 , *b*, — pole. Whereas if the contact s_2, l_2 is closed, the circuit will be: + pole, *a*, s_2, l_2 , left-hand winding of the field, relay B , contacts 11 and 12, *b*, — pole. By energizing the right or the left winding of the field, the magnetic poles are changed and the motor m_2 therefore will revolve in one or the other direction. This operation takes place until the contacts s_1, l_1 or s_2, r_2 are broken by the rotation of the disc k_2 above referred to and the motor current circuits are interrupted.

Since the transfer of the movement of the motor m_1 to the object to be adjusted is effected by means of a smaller gear-ratio than that of the motor m_2 for fine adjustment the latter may be of much smaller dimensions than the former. With a view to preventing the flow of the entire closed circuit current into the small motor it is, therefore, advisable to insert a resistance

w_1 in series with the armature of the small motor which when exciting the stator winding of this motor by the operation of the receiver e_2 and of the contacts 11, 12 is cut out of circuit by means of armature contacts 13, 14 of a relay B put in the motor current circuit.

Referring to the system shown in Fig. 2, only one motor m_3 is employed for adjusting the objects, said motor being thrown into circuit for coarse adjustment by means of the relays R_4, R_5 actuated by the receiver e_1 and for fine adjustment by means of the relays R_6, R_7 actuated by the receiver e_2 . The field of the motor m_3 is constantly energized from the net. If one of the relays R_4, R_5 , is energized by the receiver e_1 the circuit of the armature m_3 corresponds to that of the motor m_1 described in Fig. 1. The relays R_6 and R_7 do not operate when the relays R_4, R_5 are being excited, since their exciting circuits are broken at the armature contacts 15 and 17, respectively. The circuits of the relays R_6, R_7 , when the relays R_4, R_5 are deenergized are as follows: + pole, *a*, contacts 15 and 17 of the released armatures R_4, R_5 , contacts of the receiver e_2 , relays R_6 or R_7 , — pole. When the relay R_7 has attracted its armature, the circuit of the armature of motor m_3 is closed by way of: + pole, *a*, left-hand contact of the relay armature, right brush of the motor, left brush, resistance w_1 , right-hand contact 20 of the attracted armature, *b*, — pole. If the relay R_6 attracts its armature, the direction of the current is reversed as follows: + pole, *a*, contact 19, resistance w_1 , left brush of armature m_3 , right brush, right-hand contact of the attracted armature, *b*, — pole. When operating the motor m_3 for fine adjustments a series resistance w_1 is thrown into circuit by means of the working contact 19 or 20 of the operating relay R_6 or R_7 , respectively, with a view to reducing the number of revolutions of the motor m_3 the stationary exciting windings of which are permanently connected with the net work *a, b*. In the normal positions of the relay armatures the motor armature m_3 is preferably shortcircuited by means of the contacts 16 and 18 over the resistance w_2 . In addition an eddy current brake S may be provided the magnet k of which is energized in the circuit *a, 15, 17, k, 21, 22, b*, after all relays have been deenergized.

The action of eddy current brake S is shown in Fig. 3, the shaft of motor m_4 carries a metallic disk S for instance of copper, aluminum or any other suitable material, rotating between the two poles of the magnet k , the circuit of which is shown in Fig. 2.

Instead of the relays R other switch gears may be used without changing the scope and ideas involved in the present invention.

Each of the motors m_1 , m_2 , per se may also influence the object to be adjusted without an intermediate differential gear as is shown for example in U. S. Patent No. 1,123,067, 5 concerning a similarly operating system. If one single motor is used for both kinds of adjustment the speed of rotation may be reduced for fine adjustment by the eddy current brake, the magnet k of which, then, is 10 directly connected with the source of current by the line 23, shortcircuiting the contacts 21, 22 as shown in Fig. 4. The transmitting device may be provided with transmitters which are independently adjustable 15 from each other as shown in my copending application Serial No. 439,649 filed January 24th, 1921, or only a single transmitter may be provided which is adapted for both kinds of adjustment as shown for instance 20 in the British Patent No. 28,822 of 1913.

I claim:

1. In a signalling system for the tele-control of motor operated objects, two sets of electrical transmitters and receivers 25 adapted to transmit different kinds of object adjustments, means, electrically controlled by the adjustment of one of said receivers, adapted to control the motor operation, other means electrically controlled by the 30 adjustment of the other of said receivers also adapted to control the motor operation, and contact means suitably controlled by said first-named means and adapted to make operative said other means to permit both 35 controlling means only successively to cause the motor operation according to the adjusted positions of said receivers.
2. In a signalling system for the tele-control of motor operated objects, two sets 40 of electrical transmitters and receivers adapted to transmit different kinds of object adjustments, a switching device electrically controlled by the adjustment of one of said receivers adapted to control the 45 motor operation, means electrically con-

trolled by the adjustment of the other of said receivers also adapted to control the motor operation and contact means suitably controlled by said switching device to permit said switching device and said first-named means only successively to cause the motor operation according to the adjusted positions of said receivers.

3. In a signalling system for the tele-control of motor operated objects, two sets 55 of electrical transmitters and receivers adapted to transmit different kinds of object adjustments, switching relays energized by way of one of said receivers adapted to control the motor operation, means electrically 60 controlled by the other of said receivers also adapted to control the motor operation, and contact means suitably controlled by said switching relays to permit at first said switching relays to cause the motor operation 65 according to the adjusted position of one receiver and then to permit said first-named means to cause the motor operation according to the adjusted position of the other receiver.

4. In a signalling system for the tele-control of objects, electrical transmitters and receivers for transmitting coarse and fine adjustment positions for the object, a motor for adjusting the several positions of the object, switching relays for said motor and circuit connections between said relays and said motor for causing the motor to coarsely or finely adjust the object, circuit connections between said receivers and said relays for 70 controlling the relay operation, and a resistance in the motor circuit for fine adjustment, controlled by the relays actuated by the coarse receiver, said last-named relays, when energized, closing the motor circuit 75 for coarse adjustment and opening the motor circuit for fine adjustment.

In testimony whereof I affix my signature.

PAUL KAMINSKI.
